CLAIM

The ornamental design for a hood, as shown.

DESCRIPTION

FIG. 1 is a front view of a hood showing my new design;
FIG. 2 is a back view thereof;
FIG. 3 is a right side view thereof;
FIG. 4 is a left side view thereof;
FIG. 5 is a top plan view thereof;
FIG. 6 is a bottom view thererof;
FIG. 7 is a side view thereof, showing a hood in partially used condition; and,
FIG. 8 is a side view thereof showing a hood in fully used condition.

The broken lines showing of a human head in FIG. 7 and a human head with hat in FIG. 8 are for illustrative purposes only and form no part of the claimed design. The broken lines shown on the sweatband and flap of the hood represent stitching.
